RADIATOR

Original Filed Sept. 9, 1924

Inventor

THOMAS E. MURRAY

By His Attorney

N. Anthony Mina

UNITED STATES PATENT OFFICE

THOMAS E. MURRAY, OF BROOKLYN, NEW YORK, ASSIGNOR TO MURRAY MANAGEMENT CORPORATION, A CORPORATION OF NEW YORK

RADIATOR

Original application filed September 9, 1924, Serial No. 736,793. Divided and this application filed January 9, 1929. Serial No. 331,347.

This application is a division of my previous application No. 736,793, filed September 9th, 1924. The invention aims to provide a radiator using electric heating means and having considerable advantages in economy and efficiency. The single figure of the drawing is a perspective view, partly in section, illustrating the invention as applied to a design of radiator described in my application No. 188,890, filed May 5th, 1927, as a substitute for a previous application No. 725,559, filed July 12th, 1924.

Referring to the embodiment of the invention illustrated, an admission pipe 1 admits steam or other heating medium to a long, narrow rectangular chamber 2 in which it gives up its heat or a considerable portion thereof and from which it passes out by the outlet pipe 3.

The sides of the chamber are engaged by a radiating structure of plates extending laterally outward. The radiating plates at one side of the chamber are preferably made from a single continuous sheet bent to shape; and those on the opposite side from a similar sheet. Each sheet is thus formed into plates 4 and 5, separated at their inner edges to form triangular spaces or chimneys for the upward circulation of air. At their inner edges where they join the central chamber 2 there is a short plate 6 bearing against and preferably welded to the chamber so as to take the heat therefrom and conduct it outward through the parts 4 and 5. The plates 4 and 5 of each pair come together at their outer edges 7, where they are braced by longitudinal braces 8, preferably in the form of angle bars embracing the corners of the radiating structure, and thus serving also to prevent accidental contact of a person with such corners. The radiating structure thus described differs in detail from that illustrated in my previous application but is substantially the same in operation.

It can be more economically constructed because of the utilization of a single sheet to form all the radiating members at either side of the central chamber, and it has certain advantages in providing for the convenient application of other heating means.

Extending immediately below the chamber 2 is a pipe 9 for gas or similar fuel admitted through a cock 10. The pipe or burner 9 has orifices 11, preferably at intervals corresponding to the points of the heating chamber which lie opposite the separated inner edges of the plates 4 and 5. Thus when the gas is ignited the flames will lie under the chamber 2 and in the lower ends of the triangular chimneys formed by the plates 4 and 5 and the sides of the chamber. For use with gas it is desirable that hot water be supplied to the chamber. The pipe 1 at the bottom and the pipe 12 at the top may be used for introducing and withdrawing such water or for permitting the escape of steam.

A third heating means is illustrated, consisting of coils 13 of resistant wire suitably insulated and mounted in the outside spaces between the plates 4 and 5. A cable 14 is illustrated for attachment to a socket to connect the electric heaters to the circuit.

I prefer to use for the heating chamber and for the radiating structure a metal of great heat conductivity, such as copper, brass or zinc, which are much superior to the ordinary metals, iron and steel. By using copper or brass in thin sheets I get a sufficient increase in efficiency to compensate for the increased cost per pound. For example, I may use plates of about one-sixty-fourth of an inch in thickness extending outward from one to six inches. The chamber 2 should be narrow, as indicated. Radiators of this design and of these materials and dimensions are particularly advantageous because they can be easily equipped with gas boilers and electric heaters in the manner indicated, and these heaters can be located so as to secure the best application of the heat to water carried in the chamber 2, the chamber being equally adapted for steam or hot water circulation. The electric heaters stiffen the entire structure against distortion, which is important with such thin sheet metal. It will be observed that the gas flames and the electric heaters are applied at alternate points along the sides of the chamber. The gas flames come up through the chimneys formed by the sides of the chamber, while the electric heaters are

in the angular spaces which are open to the outside. It is contemplated that the radiator shall be equipped with both these heating instrumentalities, as well as with couplings to which pipes may be attached for steam or hot water circulation. If any one of these methods does not give the required amount of heat, two, or even three, of them can be used at the same time, there being no interference between them.

10 The radiator may be equally used for cooling air by circulating cold brine or the like through the pipes so that the latter become a heating element only in the negative sense, that is, they extract heat from the radiating structure and induce a flow of the cool air downward through the flues similar to the upward circulation of air induced by the passage of steam through the pipe.

15 An important feature of the invention is in the vertical extension of the transverse plates formed by the corrugated structure. These plates extend to a great height relatively to their width so as to form heated vertical air ducts which are unimpeded throughout their height. That is to say, the electric heating elements are of the same cross-section throughout their length, leaving the clear duct space between the transverse plates also of uniform section throughout their height. The cool air enters the lower ends and open sides of these air ducts and rises between the walls formed by the plates in the form of horizontal series of vertical columns of air which are progressively heated on both sides by prolonged contact with the heated walls of the ducts and are thus impelled rapidly upward so as to accelerate the circulation of the heated air columns upward from the ducts and throughout the room or enclosure to be heated.

20 The ducts between transverse plates which converge at their outer edges are in fact flues closed in cross-section and adapted to produce an even greater draft upward than the space between such flues; the draft being slower in the latter because of the admission of cool air at the open side of the duct. The action takes place either with or without water in the water chamber 2, the effect of water therein being merely to maintain a store of heat for a certain length of time after the electric current is cut off.

25 The ducts act in the same way when the heat is supplied from the fuel pipe or burner 9, this burner in fact constitutes a heating element located solely at the bottom of the ducts described; in contrast with the electric heating devices which are attached to the transverse plates not only at the lower portions of the latter, but throughout their height.

30 The result of this structure of vertical ducts is that instead of a relatively stationary or 65 slowing and laterally diffusing over

heated body of air around a heating element and underheated air in the remainder of the room or inclosure, there is obtained a greatly accelerated ascent of warm columns of air through the heated ducts and upward therefrom and thus a forced circulation and distribution of evenly heated air throughout the entire enclosure.

35 The present application is directed to radiators heated by electricity, the parent application including not only the electrical but also the other heating means described.

40 Various modifications may be made by those skilled in the art without departing from the invention as defined in the following claims.

45 What I claim is:

1. A combination heater and radiator including in combination a chamber of thin metal for a fluid heating medium on the outer face of which is mounted a radiating structure comprising vertically extending plates and electric heaters applied to the outside of the chamber so as to heat water therein and located in the spaces between said plates so as 50 to stiffen the entire structure.

55 2. A combination heater and radiator including in combination a chamber of thin metal for a fluid heating medium having flat vertical sides, a radiating structure of plates engaging the sides of the chamber, extending laterally outward and forming with the chamber wall closed vertical flues spaced apart from one another and electric heaters located in the spaces between the flues so as 100 to stiffen the entire structure and adjacent to the chamber so as to heat water therein.

60 3. An electric heater comprising vertical electric heating means and a longitudinal series of transverse, vertical heat conducting plates fixed at their inner portions in close heat conducting relation to, but electrically insulated from, said heating means, said plates being substantially free of intervening obstructions, the height of said plates being 110 relatively great compared with their width, and forming a series of unimpeded heated vertical air ducts.

65 In witness whereof, I have hereunto signed my name.
